Primary Examiner — Jennifer Rivard*Assistant Examiner* — Alison M Ofstun*(74) Attorney, Agent, or Firm* — Mitchell Law PLLC;
Matthew W. Mitchell**(57) CLAIM**

The ornamental design for an electrical and cabling housing, as shown and described.

DESCRIPTION

FIG. 1 is a front isometric view of an electrical and cabling housing showing my new design;

FIG. 2 is a front view thereof;

FIG. 3 is a back view thereof;

FIG. 4 is a left-side view thereof;

FIG. 5 is a right-side view thereof; and,

FIG. 6 is a top plan view thereof.

The article is shown with a symbolic break in its length. The appearance of any portion of the article between the break lines forms no part of the claimed design. In the drawings, the broken lines illustrate portions of the article which form no part of the claimed design.
